WILLIAM E. CRANDALL, OF NEW YORK, N. Y.

Letters Patent No. 106,033, dated August 2, 1870.

IMPROVEMENT IN HANDLES FOR CHILDREN'S CARRIAGES AND PERAMBULATORS.

The Schedule referred to in these Letters Patent and making part of the same

To all whom it may concern:

Be it known that I, WILLIAM E. CRANDALL, of the city, county, and State of New York, have invented certain new and useful Improvements in Handles for Children's Carriages or Perambulators; and I do hereby declare that the following is a full, clear, and exact description of the construction thereof, sufficient to enable any one skilled in the art to which my invention appertains to make and use the same, reference being had to the accompanying drawing making a part of this specification, in which drawing—

Figure 1 is a front elevation of my devices.

Figure 2 is a side view of the adjustable handle.

Figure 3 is a central longitudinal section of the same.

Like letters of reference indicate corresponding parts in each figure.

Heretofore it has been customary in constructing children's carriages or perambulators to provide the same with a pushing or pulling handle, which consisted of two bent arms attached at one end to the body or axles of the carriage, while the other ends were braced by an ordinary bar or handle, made of wood or metal, in such a manner that the person in using the carriage seized the bar or handle, by which means the carriage was either pushed or pulled from point to point.

The employment of such handles have met many objections in the use of such class of carriages, since the handle not only becomes mutilated by constant use, but, at the same time, the person using the carriage is apt to lose control of the handle when the wheels of the carriage come in contact with gutters or other sudden obstructions upon the streets.

To remedy these defects is the object of this invention; and to this end,

It consists in providing each end of the ordinary bar or handle of a child's carriage with a stationary secondary handle, made of metal or other suitable material.

Also, in providing such ordinary bar or handle with a secondary adjustable handle at each end; and, furthermore, in providing such ordinary bar or handle with a single stationary or adjustable secondary handle, which may be located at or near the center part of the said ordinary bar or handle, all of which will hereinafter be more fully set forth.

In the drawing—

A may represent the ordinary bar or handle of a child's carriage attached to the bent or straight arms B B, the latter of which are designed to be attached to the body or axles of the said carriage or perambulator.

Upon each end of the bar or handle A is secured, in any suitable manner, a secondary handle, D,

This secondary handle D is made of any suitable metal or material, and is formed or otherwise provided with a suitable ferrule, D', which, together with the portion composing the handle, embraces the ends of the bar or handle any desired distance toward the center of the said bar or handle.

In this instance it is designed to retain the secondary handle always in one position relatively to the ordinary bar or handle of the carriage when properly placed and secured thereon.

In further carrying out the object of the invention, the secondary handles are formed so as to be adjustable, and it consists in making the handle E separate from the ferrule D', in such a manner that when the handle E is placed upon the ordinary bar or handle, and the ferrule secured in its place, that the handle may be turned or revolved upon the said ordinary bar or handle A, as clearly shown in fig. 1.

When the handle is thus formed in two separate pieces, the ferrule is formed with one or more slots, a, while the ring portion of the handle is also formed with a series of corresponding slots, a' a', within, and between which is interposed a catch-pawl, b, which operates so as to engage with either of the slots a a'.

This catch-pawl may be pivoted at one end, and a suitable spring placed within the recess a', by which means the catch-pawl is constantly held within either of the slots when it is designed to raise or lower the handle to suit the height of different persons.

An elastic piece of rubber, or its equivalent, may be used instead of the spring, so as to force and retain the catch-pawl in either of the slots.

Instead of the secondary handle being located at or near the end of the ordinary handle, a single stationary handle may be used, and located at or about the center of the ordinary bar or handle.

H may represent such a handle, formed or provided with a ring, H', which embraces, more or less, the entire circumference of the ordinary handle.

To further increase the utility and adaptability of the single secondary handle H, the same is rendered adjustable by means of a slot, h, or its equivalent, formed with the ring H', in such a manner as to receive a set-screw, wedge, or their equivalents.

This set-screw may be provided with a suitable handle, so as to allow it to be easily operated, the screw portion of the same entering either a short distance into the ordinary bar or handle, or may pass entirely through the same, as may be desired.

A nut, f, may be used, and inserted at various points upon the ordinary bar or handle, the screw portion of the set-screw to enter, thus obviating any tendency of the material being injured if wood be used in the construction of the said ordinary bar or handle.

When the single secondary handle H is used, the bar or handle A is inserted into the ring before it is

applied to the arms B B, and to prevent any wearing or injury to the surface of the bar or handle A the same may be covered with raw-hide, or other suitable material, at the point where the ring H' is placed, or the ring may itself be lined upon the inside with like material.

These handles, with their ferrules or rings, may be plated or not, as desired, but it is preferred to cover or coat the same with some suitable white metal.

The ordinary bar or handle A may be formed with either of the handles, in one piece, from any suitable metal, in which case the said bar is provided with sockets, by which means it can readily be attached to the arms B B.

Various designs or configurations of any desired form may also be placed upon or formed with the handles, ferrules, or rings, and to such features the invention is not limited.

Neither is the invention limited to any particular form, construction, or mere transposition of the handles upon the ring or ferrules.

It will also be readily understood that either of the metallic handles may be formed with or arranged in an oblique, vertical, longitudinal, or any other suitable manner, in reference to the ferrules or rings, as may be desired.

Thus it will be seen that I have produced a secondary handle, which is readily applied to the ordinary bar or handle of old or new carriages or perambulators, which, when either plated or ornamented, adds greatly to the beauty of such carriages, at the same time afford a firm support for the hand or hands of those pushing or pulling the carriage.

Having described my invention,

What I claim as new, and desire to secure by Letters Patent, is—

1. The combination, with the ordinary bar or handle of a child's carriage or perambulator, of one or more secondary handles, substantially as described.

2. The secondary handles D, provided with the ferrules D', in combination with the ordinary bar or handle of a child's carriage or perambulator, substantially as described, for the purpose set forth.

3. The secondary adjustable handles E, in combination with the metallic ferrules D", and the ordinary handle of a child's carriage, substantially as described.

4. The slots a a, formed in the ring portion of the secondary handles with the slotted ferrules D", in combination with a catch-pawl and a spring, or their equivalents, substantially as described, for the purpose set forth.

5. The single secondary handle, so constructed as to be placed at or near the center of the ordinary bar or handle of a child's carriage or perambulator, substantially as described, for the purpose set forth.

6. The single secondary handle H, formed or provided with a slotted ring, H', in combination with a set-screw, or its equivalent, and the ordinary bar or handle of a child's carriage or perambulator.

To the above I have signed my name this 14th day of July, 1870.

WM. E. CRANDALL.
